(57) CLAIM

The ornamental design for a pill holder and dispenser, as shown and described.

DESCRIPTION

FIG. 1 is a top plan view of the claimed embodiment of the pill holder and dispenser;

FIG. 2 is a bottom plan view of the embodiment of FIG. 1; and,

FIG. 3 is a side elevation view of the embodiment of FIG. 1.

The broken line showing of the chain and ring support in FIGS. 1-3 is for illustrative purposes only and forms no part of the claimed design.
